UNITED STATES PATENT OFFICE.

WILLIAM E. RANNEY, OF COLUMBUS, OHIO, ASSIGNOR TO THE PERFECTION MORTISER COMPANY, OF COLUMBUS, OHIO, A CORPORATION OF OHIO.

MORTISING MACHINE.

Application filed August 21, 1924, Serial No. 733,437. Renewed April 17, 1928.

This invention relates to improvements in of the screws. Arising centrally from the wood working machines, and has for its top of the section 7 are guide rods 10, which principal object the provision of an improved power driven machine for producing have their outer ends united by means of a transverse cross piece 11. This mortises, recesses and sockets within doors, construction provides a frame of strong durable 60 sashes or the like, and consists in the provision of an improved portable machine capable of being readily applied to the edge of a door or the like and including a power driven upon the rods 10 is the carriage 4 which is 65 drill or bit having an oscillatory motion preferably in the form of a casting having bowed side walls 13 and sleeve shaped outer which upon operation will serve to produce extensions 14 suitably bored for the reception within the edge of the door a mortise of desired formation, the operation being quickly 70 accomplished and in a labor and cost saving manner over ordinary methods. 75

With these and other objects in view, as will appear as the description proceeds, the invention consists in the novel features of construction, combinations of elements and 20 arrangements of parts hereinafter to be fully described and pointed out in the appended claims. 80

In the drawings:

Figure 1 is a front elevation of the improved mortising machine comprising the present invention, 85

Figure 2 is a vertical section taken on the line 2—2 of Figure 1,

Figure 3 is a horizontal sectional view on 30 the line 3—3 of Figure 1, and

Figure 4 is a detail view of the bit supporting means.

Referring more particularly to the drawings the numeral 1 designates my improved 35 mortising machine in its entirety. This machine consists broadly of a frame adapted for clamping engagement with the edge of a door 3 or other similar article; a carriage 4 is slidably mounted on the frame for longitudinal travel thereon and carries a motor 5 which is employed to impart power to a 40 rotary and oscillatory bit 6. 90

The frame 2 is of substantially rectangular form and comprises a lower section 7 of substantially channel shaped formation, having spaced vertical side walls which receive between them the edge of the door 3, as shown in Figure 2. In securing the frame in an applied position upon the door, the 45 side walls of the lower section have their ends provided with threaded openings for the reception of clamping screws 8, which have their inner ends provided with heads 9 adapted to be frictionally engaged with 50 the sides of the door upon the manipulation 95

In order to oscillate the bit so as to produce a mortise of required length, the upper end of the motor is provided with a housing 28 in which is positioned suitable speed reduction gearing (not shown), for the purpose of imparting relatively slow rotary motion to a shaft 29 upon which is fixed for rotation a crank 30. This crank 100

has its outer face provided with a longitudinal slot 31 in which is adjustably clamped a block 32. This adjustable clamping of the block at any desired position within the 5 length of the slot 31 is accomplished by the provision of a screw 33, which is threaded into an opening formed in the block 32 and is shouldered as at 34 to frictionally engage with a binding washer 35. It will be 10 manifest that by tightening the screw the block may be positioned at any point in the length of the slot 31. The outer end of the screw 33 is enlarged to provide a bearing 15 for the outer end of a link 36, which link has its inner end pivoted as at 37 to a crank 38 extending outwardly from the yoke bracket 24, which is journaled for oscillatory movement upon the shaft 19 of the motor.

20 In view of the foregoing it will be seen that when the motor 18 is energized the drill or bit 6 will be rapidly rotated at approximately the speed of the armature shaft of the motor. The oscillatory speed of 25 travel, however, of the bit is materially low, and this is accomplished through the slow turning crank 30 which oscillates the yoke bracket 24 and the bit 6. Since the drive gear 21 is located on the shaft 19, and the 30 yoke shaped bracket swings about the axis of said shaft it will be apparent that power will be imparted to the bit in any position of its path of oscillatory travel. Further, by reason of the adjustable block 32, the 35 effective throw of the crank 30 may be varied so that the path of travel of the bit may be adjusted to produce a mortise of desired length. In the event that the bit is merely employed for boring holes, the block is positioned so that the screw 33 is axially aligned 40 with the shaft 29.

What is claimed is:

1. In a mortising machine, a frame, a carriage mounted upon said frame for longitudinal travel, a motor stationarily positioned upon said carriage, a bit, power transmission devices between said motor and bit, and means for oscillating said bit during the 45 operation of said motor.
- 50 2. In a mortising machine, a frame, a carriage on said frame movable longitudinally thereof, a motor mounted stationarily

on said carriage, a bit, power transmission devices between said motor and bit permitting of the oscillation of said bit relative to said motor, and means for oscillating the bit. 55

3. In a mortising machine, a frame, a carriage slidable on said frame, a motor stationarily supported on said carriage, a bit, power transmission devices between said motor and bit for rotating and oscillating said bit by power derived from said motor, and means for effecting sliding movement 60 of the carriage on said frame. 65

4. In a mortising machine, a frame, a carriage slidable on the frame, a motor on the carriage, a bit, power transmitting devices between said motor and bit for rotating the latter and permitting of the oscillation of said bit relative to said motor, and continuously acting means driven by the motor for effecting the oscillation of said bit. 70

5. In a mortising machine, a frame, a carriage slidable on said frame, a motor positioned upon said carriage, a bit, power transmitting devices between said motor and bit for rotating the latter and permitting of oscillatory movement on the part of said 75 bit, means for oscillating said bit by power derived from said motor, and manually operated means for causing longitudinal traverse of the carriage on said frame. 80

6. In a mortising machine, a frame, a carriage slidable on the frame, a motor on said carriage, a transverse shaft driven by said motor, a bit holder arranged to oscillate about the axis of said shaft, a bit in said holder, power transmitting devices between said shaft and bit, and means for effecting the oscillation of said bit holder. 85 90

7. In a mortising machine, a frame, a carriage slidable on the frame, a motor on said carriage, a transverse shaft driven by said motor, a bit, power transmitting devices between said motor and said bit, a bit holder arranged to turn about the axis of said shaft, a means driven by said motor for effecting the oscillation of said holder and 95 said bit. 100

In testimony whereof I affix my signature.

WILLIAM E. RANNEY.
